(57) **CLAIM**

The ornamental design for a wallet as shown and described.

DESCRIPTION

FIG. 1 is a rear perspective view of a wallet;

FIG. 2 is a rear view thereof;

FIG. 3 is a front view thereof;

FIG. 4 is a top view thereof;

FIG. 5 is a bottom view thereof;

FIG. 6 is a left side view thereof; and,

FIG. 7 is a right side view thereof.

The dash-dash-dash type broken lines (e.g., showing screw holes) are for the purpose of illustrating portions of the wallet and form no part of the claimed design.

The dot-dash-dot-dash type broken lines shown in the drawings define the boundaries of the claimed design.
